Application March 2, 1936, Serial No. 66,597

6 Claims. (Cl. 242—53)

This invention relates to driving mechanism for apparatus for handling thread or the like; particularly, to driving mechanism for continuous processing apparatus of the type shown, described and claimed in prior application Serial No. 7,114, filed February 18, 1935, by Walter F. Knebusch and Alden H. Burkholder. The apparatus of said application embraces a plurality of thread-storage, thread-advancing devices disposed in processing sequence in regularly stepped arrangement, the thread or the like, hereinafter referred to as thread, being subjected to treatment while stored in generally helical form on such thread-storage, thread-advancing devices. While the driving mechanism therein shown and described is adapted to demands of greatly varying character, being characterized by an unusually high degree of flexibility, the improved driving mechanism of the present invention offers in respect of construction, operation, maintenance and the like the important advantages of greater simplicity, economy and efficiency.

The improved driving mechanism of the present invention is illustrated in the accompanying drawings, in which Figure 1 is a sectional elevation, on line 1—1 of Figure 2, showing the general arrangement of the driving mechanism for the thread-storage, thread-advancing devices. Figure 2 is a corresponding front elevation, parts being broken away for the sake of clearness. Figure 3 is an enlarged sectional elevation along line 3—3 of Figure 4 showing in more detail the lower end of the driving mechanism for the thread-storage, thread-advancing devices. Figure 4 is an elevation on the same scale along line 4—4 of Figure 3 showing the rear of the driving mechanism of Figure 3. Figure 5 is a sectional elevation on the same scale along line 5—5 of Figure 4 showing clutch mechanism which may be employed in the driving mechanism of the invention. Figures 6 and 7 are respectively a longitudinal section and an end elevation on an enlarged scale of one form of thread-storage, thread-advancing device which may be used in the apparatus shown.

The arrangement of thread-storage, thread-advancing devices in the apparatus illustrated is generally similar to that shown in said prior application. By reference to Figures 1 and 2, it can be seen that the thread-storage, thread-advancing devices of the apparatus are arranged, as in said prior application, in vertical series. Each vertical series comprises a plurality of thread-storage, thread-advancing devices bearing reference numerals 2 to 8, inclusive. In each vertical

series, a single thread is continuously subjected to one or more processing treatments on each thread-storage, thread-advancing device as it progresses downward in the series, being finally collected by cap-twister 9. The thread-storage, thread-advancing devices shown are of cantilever form; i. e., supported and driven from one end only, and are of a type such that the thread is stored thereon in a plurality of generally helical turns which are advanced axially by the action of the elements of each thread-storage, thread-advancing device. A relatively long length of thread is thus continuously temporarily stored on a single thread-storage, thread-advancing device.

In the apparatus shown, furthermore, the thread-storage, thread-advancing devices in each vertical series are disposed in stepped arrangement with the thread-receiving end of each device adjacent the thread-discharge end of the preceding device, the open ends of the thread-storage, thread-advancing devices being presented toward the operator. This arrangement provides important advantages in allowing access to the thread-storage, thread-advancing devices for starting the thread thereon, inspection, repair, etc. In addition, thread-storage, thread-advancing devices in adjacent vertical series may be disposed in corresponding positions, thus providing advantages in construction of the processing medium supply and removal systems, since such systems may extend longitudinally of the machine and serve all thread-storage, thread-advancing devices in corresponding positions. The thread-storage, thread-advancing devices are thus arranged in a plurality of vertical series in a bank inclined as a whole from the vertical.

The thread-storage, thread-advancing devices may take the form of reels of the form illustrated in Figures 6 and 7. These reels operate on the principle of the reel shown, described and claimed in British Patent No. 413,414. From Figures 6 and 7 it can be seen that each reel comprises two rigid, generally cylindrical members 11 and 12. Member 11, which may be termed the concentric member, is mounted concentrically upon and for rotation with drive shaft 13, and has its periphery comprising a plurality of bar members 14. Member 12, which may be termed the eccentric member, is rotatably mounted with its axis slightly offset from and inclined to that of the concentric member and has its periphery comprising a plurality of bar members 15 equal in number to bar members 14 and alternately disposed therewith.

Concentric member 11 may be formed as

shown, having the bar members 14 formed on the periphery of a hollow cylindrical body 16, in which case great rigidity is imparted to the bar members 14. While member 11 may be mounted 5 on the drive shaft 13 in various manners, in that shown it is held against shoulder 17, formed on drive shaft 13, by cap nut 18 which is threaded on the end of reel drive shaft 13. Member 11 is caused to rotate with the shaft 13 by means of a pin 19 through the shaft 13, the projecting ends of which pin extend into a slot 21 formed in the hub 22 of concentric member 11. The projecting end of the drive shaft 13 and the nut 18 are thus contained within the body 16 of member 11 and 10 therefore protected from any processing liquids which may be used.

The bar members 15 of eccentric member 12 may be provided at their outer ends with an annular reinforcing rib 23, and be supported from 20 a ring-like portion 24 at their inner ends. Eccentric member 12 may thus constitute an extremely rigid, generally cylindrical cage-like member 25 mounted on a rigid annular supporting member 26, as by bolts 27. Annular supporting member 26 is rotatably supported in offset and inclined position with respect to the axis of concentric member 11 by being mounted in the desired position on frame member 28, the shaft 13 being journaled in or otherwise supported in correct relationship with frame member 28. A bushing 29 may be provided in annular supporting member 26 to act as a bearing if desired. Flexible sealing means 31 may be provided, if desired, to prevent corrosion of the bearing members.

35 Rotation of the reel drive shaft 13 causes concentric member 11 fixed thereto to rotate, whereupon contact of bar members 14 of concentric member 11 with bar members 15 of eccentric member 12 causes said eccentric member to rotate 40 at the same angular speed. During such rotation, the offset relationship of the generally cylindrical members 11 and 12 causes the thread to transfer from the bar members of one generally cylindrical member to the bar members of the other generally 45 cylindrical member. At the same time the inclined relationship of said generally cylindrical members causes the thread to advance in a plurality of spaced generally helical turns.

50 While the thread is so stored on one or more reels, various processing treatments may be applied to the thread. Thus in the apparatus shown in Figures 1 and 2, various liquid processing treatments such as bleaching, washing, soaping, etc., may be applied on certain of the reels 2, 3, 4, 5 and 6, while on reel 7 the thread may be stored 55 for an interval during which no processing medium is applied, any liquid carried by the thread from the preceding liquid processing stage being allowed to drip from the thread before it is dried 60 on the reel 8. The processing liquid may be applied to the thread on the reel in each liquid processing stage from a reagent distributor 32 positioned above such reel, said reagent distributor being supplied from a conduit 33 which 65 may extend longitudinally of the machine and serve all like reels in a horizontal series. The processing liquid may be collected in a trough 34 beneath each reel which may likewise extend longitudinally of the machine and serve all corresponding reels in a horizontal series. Reel 8, which, in the apparatus shown, is enclosed by chamber 35 and is used for the drying of the thread, may be supplied with a drying medium, such as heated air, through hollow shaft 13a.

70 The driving mechanism shown, which embodies

the present invention, comprises a main drive shaft 36 which is adapted to drive, as, for example, through gears 37 and 38, a plurality of upwardly extending shafts 39 herein called intermediate drive shafts. Each drive shaft 39 drives 5 each reel of a descending vertical series of reels through one of the stub shafts 13. The latter may be driven, as by gears 42 and 43, from the corresponding intermediate drive shaft. While the intermediate drive shafts 39 are shown as 10 driven from their lower ends from a common main drive shaft 36, it is apparent that the intermediate drive shafts 39 may, without departing from the spirit of the invention, readily be driven, whether in common, in groups or individually, by 15 various other means.

Each such upwardly extending intermediate drive shaft 39 may be disposed parallel to the front of the inclined bank formed by the reels; i. e., at an angle to the vertical, in which case 20 each intermediate drive shaft 39 may conveniently have disposed along its length a plurality of drive shafts 13, each adapted to drive a reel. Drive shafts 13 are preferably positioned with their axes parallel to each other 25 but inclined to the axis of intermediate drive shaft 39. It is preferable, as in the apparatus illustrated, to have all intermediate drive shafts 39 parallel to each other and disposed in or at least parallel to a common oblique plane parallel to the 30 main drive shaft 36.

In the apparatus shown, the frame member 28 of each reel is provided with a bracket 44 by means of which the reels in each vertical series are mounted in the desired position on one of the 35 inclined beams 45 which form part of the framework of the machine. There are as many such inclined beams 45 as there are vertical series of reels, all extending upward at a common angle to the vertical. The intermediate drive shaft 39 40 for each vertical series of reels is mounted, as shown in Figures 1, 2 and 3, along a corresponding inclined beam 45 as by means of the main bracket 47 at the lower end of shaft 39 and one or more bearing brackets 46. Each main bracket 45 47 comprises a journaled support 48 for the secondary drive shaft 39 and a support 49 in which is journaled the hollow drive shaft 13a of the dryer reel 8 and in which is mounted the end of the supply duct 50 for the drying medium 50 furnished to the hollow drive shaft 13a.

If desired, a trough 52 to serve as a lubricant reservoir may be mounted on each bracket 47 to enclose the lower end of each helical gear 37. Helical gears 37 are, in the apparatus illustrated, 55 mounted on main drive shaft 36 and engage helical gears 38, each of which is mounted to drive an intermediate drive shaft 39. The main drive shaft 36 in the apparatus shown is mounted on the frame member 51 of the machine by means of a plurality of bearing brackets 53, and is rotated by means of a chain 63 driving sprocket 64 mounted for rotation with drive shaft 36, the chain being driven from sprocket 65 mounted on shaft 66 which is caused to rotate by chain 68 65 from motor 69.

70 It has been found desirable to provide means for disengaging a given vertical series of reels from the driving means, since it is often desirable to stop a vertical series of reels for inspection, adjustment, etc., without at the same time stopping the whole machine. In the apparatus shown, clutch mechanism of the form shown to advantage in Figures 4 and 5 may conveniently be provided. To this end, the helical gear 37 for each vertical 75

series of reels is rotatably mounted on main drive shaft 36, being located against a collar 54 fixed thereto. A clutch member 55, slideable along the main drive shaft 36, is keyed to said drive shaft and adapted to have its jaw teeth 56 engage corresponding teeth 57 formed on the boss of the helical gear 37. Clutch member 55 is shown as being actuated by means of a shifter fork 58 being operated by rotation of the bar member 60 to which it is fixed, which bar member 60 extends to the operating face of the machine, where it is provided with a handle 61, shown in Figures 1 and 2, easily accessible to the operator. A stop 62 on the drive shaft 36 may be provided to limit the travel of the clutch member 55 when it is disengaged. In Figure 4 the clutch at the extreme right is shown disengaged while the other two are shown in the engaged position.

The gears 42 and 43, which, in the embodiment of the invention illustrated, drive the drive shafts 13 of the thread-storage, thread-advancing devices from the drive shafts 39, may be of various types, but bevel gears have been found to be especially well adapted therefor. Bevel gears operate with less sliding action and consequently less power loss under conditions of poor lubrication than do other forms of gears which might be employed. The employment of bevel gears at this point is therefore desirable since a more complicated construction than that shown would be required to insure complete lubrication of the gears 42 and 43. It is desirable to use reinforced Bakelite as the material for gears 42 and 43 for several reasons; among them, that the initial cost of gears so made is much lower than that of like gears of metal; that the strength requirements of the gears 42 and 43 are well within the strength of such materials; and such gears are quiet running; that such gears wear well with only occasional, or even without any, lubrication; and that such gears are corrosion-resistant, which is advantageous because of the corrosive vapors or liquids, due to the processing liquids employed, to which the gears may be exposed.

The apparatus illustrated includes cap-twisters 9, comprising collecting devices to which the thread passes from each vertical series of reels. A plurality of cap-twisters 9 is mounted on a lifting rail 72, which is supported by brackets 73. Brackets 73 are designed to guide the lifting rail 72 in its vertical path, each comprising guide surfaces 74 which are adapted to slide on a rigidly supported guide rod 75. The lifting rail 72 is vertically reciprocated by tension members 76 fastened thereto at one end and at the other to sprockets 77 rigidly mounted on a rotatable shaft 78 extending parallel to the lifting rail. The shaft 78 is given a suitable oscillatory motion which causes the chains 76 to wind on and unwind from sprockets 77, thus vertically reciprocating lifting rail 72. This oscillatory motion is imparted to shaft 78 by chains 79 adapted to wind on and unwind from sprockets 81 rigidly mounted on shaft 78 and actuated by levers 82 from cams 83 mounted on drive shaft 84, which is driven from the shaft 66 through a speed reducer 85. Counter-weights 86, supported by chains 87 adapted to wind on and unwind from sprockets 88, may be provided to counter-balance the weight of the reciprocating parts.

The whisks 89 of each pair of adjacent cap-twisters 9 are driven by belts 91 from a rapidly rotating drum 92 which is driven by motor 93

through chain 68. Guide rollers 93, also adapted to reciprocate vertically by being supported by brackets 73, may be provided to guide the belts 91 on the whisks 89. The belt tightener 94 may also be supplied for each belt. The effect of this cap-twisting mechanism is to rapidly rotate and vertically reciprocate the bobbins of the several cap-twisters so that the thread is twisted and at the same time wound upon the bobbins in the well-known manner. Shields 95 may be provided between adjacent twisters to prevent the "balloon" formed by the thread during the operation of each twister from interfering with those of adjacent twisters.

The drive mechanism comprising the present invention is capable of various modifications and may be applied to other uses than the one in connection with which it is herein illustrated. Where, as in the case of the apparatus illustrated, the invention is employed in the continuous processing of thread, it is obvious that various modifications may be made, such, for instance, as the employment of types of thread-storage devices other than the one described, without in any way departing from the spirit of the invention. In the appended claims, the term "thread" is intended to include, besides thread per se, all other types of materials capable of being handled by the thread-storage, thread-advancing devices of the apparatus.

It is intended that the patent shall cover, by suitable expression in the appended claims, whatever features of patentable novelty reside in the invention.

What is claimed is:

1. Apparatus comprising a bank of cantilever thread-storage, thread-advancing devices arranged in a plurality of series each of which handles a single thread, said bank being inclined from the vertical; drive shafts for said thread-storage, thread-advancing devices projecting endwise from said bank, the axes of said drive shafts being substantially horizontal; a succession of upwardly extending intermediate drive shafts paralleling the plane of said bank; connecting means between said intermediate drive shafts and said projecting drive shafts for rotating said projecting drive shafts; a main drive shaft extending transversely of said intermediate drive shafts; and connecting means for rotating said intermediate drive shafts from said main drive shaft.

2. Apparatus comprising a bank of cantilever thread-storage, thread-advancing devices arranged in a plurality of series each of which handles a single thread, said bank being inclined from the vertical; drive shafts for said thread-storage, thread-advancing devices projecting endwise from said bank, the axes of said drive shafts being substantially horizontal; a succession of intermediate drive shafts paralleling the plane of said bank; connecting means between said intermediate drive shafts and said projecting drive shafts for rotating said projecting drive shafts; a main drive shaft extending transversely of and operatively connected to said intermediate drive shafts whereby said intermediate drive shafts are rotated; and clutch means for disconnecting said intermediate drive shafts from said main drive shaft.

3. Apparatus comprising an upwardly extending bank of cantilever thread-storage, thread-advancing devices arranged in a plurality of descending series each of which handles a single thread; drive shafts for said thread-storage,

- thread-advancing devices projecting endwise from said bank, the axes of said drive shafts being substantially horizontal; a plurality of upwardly extending intermediate drive shafts paralleling the plane of said bank; connecting means between each of said intermediate drive shafts and the projecting drive shafts of one of said descending series of thread-storage, thread-advancing devices; a main drive shaft extending transversely of and operatively connected to said intermediate drive shafts whereby said intermediate drive shafts are rotated; and clutch means for disconnecting said intermediate drive shafts from said main drive shaft.
4. Apparatus comprising an upwardly extending bank of cantilever thread-storage, thread-advancing devices arranged in a plurality of descending series each of which handles a single thread; drive shafts for said thread-storage, thread-advancing devices projecting endwise from said bank, the axes of said drive shafts being substantially horizontal; a plurality of upwardly extending intermediate drive shafts paralleling the plane of said bank; connecting means between each of said intermediate drive shafts and the projecting drive shafts of one of said descending series of thread-storage, thread-advancing devices; and a main drive shaft extending transversely of and operatively connected to said intermediate drive shafts, whereby said intermediate drive shafts are rotated.
5. Apparatus comprising an upwardly extending bank of cantilever thread-storage, thread-advancing devices, said thread-storage, thread-ad-

vancing devices being disposed in said bank in a plurality of series each of which handles a single thread; drive shafts for said thread-storage, thread-advancing devices projecting obliquely from the plane of said bank, said drive shafts being parallel to each other; a succession of intermediate drive shafts paralleling the plane of said bank; connecting means between said intermediate drive shafts and said projecting drive shafts for rotating said projecting drive shafts; a main drive shaft extending transversely of and operatively connected to said intermediate drive shafts whereby said intermediate drive shafts are rotated; and clutch means for disconnecting said intermediate drive shafts from said main drive shaft.

6. Apparatus comprising an upwardly extending bank of cantilever thread-storage, thread-advancing devices, said thread-storage, thread-advancing devices being disposed in said bank in a plurality of series each of which handles a single thread; drive shafts for said thread-storage, thread-advancing devices projecting obliquely from the plane of said bank, said drive shafts being parallel to each other; a succession of upwardly extending intermediate drive shafts paralleling the plane of said bank; connecting means between said intermediate drive shafts and said projecting drive shafts for rotating said projecting drive shafts; a main drive shaft extending transversely of said intermediate drive shaft; and connecting means for rotating said intermediate drive shafts from said main drive shaft.

PER J. E. ANDERSSON.
